UNITED STATES PATENT OFFICE.

HARRY T. JOHNSON, OF SCIO, NEW YORK.

MECHANICAL TELEPHONE.

SPECIFICATION forming part of Letters Patent No. 267,897, dated November 21, 1882.

Application filed June 12, 1882. (No model.)

To all whom it may concern:

Be it known that I, HARRY T. JOHNSON, of Scio, in the county of Allegany and State of New York, have invented a new and Improved 5 Mechanical Telephone, of which the following is a full, clear, and exact description.

My invention consists of an improved arrangement of the wires traversing the diaphragm for improving the vibratory action of 10 the diaphragm.

It also consists in the peculiar construction and arrangement of a double-diaphragm arrangement calculated to improve the efficiency of the sound-producing qualities of the telephone; and it also consists of certain details 15 of construction, all as hereinafter described, and pointed out in the claims.

Reference is to be had to the accompanying drawings, forming part of this specification, in 20 which similar letters of reference indicate corresponding parts in all the figures.

Figure 1 is a front elevation of my improved telephone with a part of the mouth-piece broken out. Fig. 2 is a sectional elevation of the 25 telephone, taken on line xx of Fig. 1; and Fig. 3 is a detail of my improved arrangement of the wires traversing the diaphragm.

At the center of the diaphragm a , I locate a button, b , for the purpose of connecting the 30 wires c , traversing the diaphragm, by means of studs e , so as to stretch them between studs f at the margin of the diaphragm slightly toward but not to the center from the direct line between the opposite pins f , from which 35 said wires are stretched, which avoids the running of the wires so close together as they do when stretched radially to the center, making a cluster thereat, which is less beneficial to the vibratory action of the diaphragm. Being 40 drawn in this way, they distribute the vibrations caused by sound-waves more perfectly and clearly than when drawn from the center. With the button thus attached to the wires, and the diaphragm attached to the 45 button, the diaphragm is secured much better than in an other way. The wires c and button hold the diaphragm nearly in a flat plane, whereby it has more vibratory power and clearer tone. The arrangement also causes

the sound-waves to be distributed to all parts 50 of the diaphragm in such a manner as to produce better results than without said wires. The diaphragm a is connected to a ring, g , which rests on another diaphragm, h , which is attached to the rim i of the base j , by which 55 the telephone is to be mounted on the wall or other support. Diaphragm h has a washer, k , at the center between it and the diaphragm a , and the button b , diaphragm a , washer k , and diaphragm h are all substantially connected 60 together by the screw-bolt l and nut m , the nut being screwed up so as to clamp them all tightly together, and to this screw-bolt the transmitting-wire n is attached. The mouth-piece o , which is here represented with a round 65 opening, but which may be square, is attached by its flange p and screws q , with the ring i of the base, with springs s between them to press it against the heads of the screws and prevent it from bearing on the diaphragm a . 70

Posts may be employed instead of the screws and springs; but I prefer the screws, in order that the mouth-piece may be adjusted nicely with respect to the diaphragm.

The diaphragms a and h may be made of 75 sheep-skin, silk, or other suitable material. The transmitting-line n may be made of copper, iron, brass, or cotton cord. The objects of using two diaphragms are to provide a dead-air space to prevent the noises caused by the 80 wind blowing against the line-wire, and to increase the sensitiveness of diaphragm a by resting on the diaphragm h , which forms a kind of sounding-board that produces clear tones, and to enable the diaphragm a to vibrate much easier, whereby it is a much better transmitter for long lines. 85

Cords may be used instead of the wires c stretched across the diaphragm a .

Having thus fully described my invention, I 90 claim as new and desire to secure by Letters Patent—

1. The combination, with cords or wires c , stretched across the diaphragm a , of the button b and studs e , substantially as described. 95
2. In a telephone, the combination, with the base i , provided with the diaphragm h , of the diaphragm a , of less diameter than the dia-

phragm *h*, rigidly secured at its center to the said diaphragm, and provided with the ring *g*, secured to its edge and bearing upon the diaphragm *h*, substantially as and for the purpose set forth.

3. The combination, with base *i*, provided with the diaphragm *h*, of the diaphragm *a*, provided with the ring *g*, the mouth-piece *o*, and the adjusting-screws *q*, substantially as and for the purpose set forth.

4. The combination, with the base *i*, pro-

vided with the diaphragm *h*, the mouth-piece *o*, the diaphragm *a*, provided with the ring *g*, and interposed between the mouth-piece and the diaphragm of the base, of the adjusting-screws *q*, and the springs *s*, substantially as and for the purpose set forth. 15

HARRY T. JOHNSON.
